UNITED STATES PATENT OFFICE.

JAMES GEORGE ADDERSON, OF RENTON, WASHINGTON, ASSIGNOR TO DENNY-RENTON CLAY & COAL COMPANY, OF SEATTLE, WASHINGTON, A CORPORATION OF WASHINGTON.

BRICKMAKING-MACHINE.

1,179,383.

Specification of Letters Patent.

Patented Apr. 18, 1916.

Application filed June 13, 1914. Serial No. 844,916.

To all whom it may concern:

Be it known that I, JAMES GEORGE ADDERSON, a citizen of the United States, residing at Renton, in the county of King and State of Washington, have invented certain new and useful Improvements in Brick-making-Machines, of which the following is a specification.

This invention relates to improvements in machines for making paving brick.

Side-cut bricks are found to be desirable and are in increasing demand for paving and other analogous uses where a tough and wear-resistant block is required, owing to its relatively homogeneous character and the practically even texture of its material throughout its entire body. In being pressed through the die, the surface of the clay column coming in contact with the die assumes a somewhat different molecular arrangement than the interior portion of the column and to the extent that this difference of structure is present, the brick is liable to disintegrate under severe usage. It is evident that with side-cut brick the surface molded by the walls of the die are reduced to a minimum and hence have found favor for paving-brick.

A disadvantage heretofore attendant upon side-cut brick has been that it has not been practicable to form the longitudinal beveled edges or form the side legs for spacing the brick apart in the pavement. It is to provide devices for the accomplishment of such refinements to the brick that this application deals.

One of the objects of the invention is the provision of automatic means for raising side spacing lugs upon one or both of the side cut edges of the clay blocks.

A further object of the invention is the provision of automatic means for forming beveled or rounded corners upon the upper lateral sides of side-cut clay blocks as delivered from the cutting table.

A still further object of the invention consists in the provision of means of simple construction and efficient operation for turning side-cut clay blocks wherein their longitudinal axis extends transversely to the direction of their travel to positions wherein said axis extends longitudinally with such direction of travel.

A still further object of the invention is the provision of means to advance a column of clay blocks arranged in end-to-end rela-

tion between suitable guides to be worked upon by forming devices, as outlined.

The invention consists in the novel construction, combination and adaptation of clay-block-forming apparatus with the above objects in view, as will be fully described in the following specification, illustrated in the accompanying drawings and finally set forth in the appended claims.

Referring to said drawings, Figure 1 is a view in side elevation of clay-block forming apparatus embodying my invention. Fig. 2 is a plan view of the same. Fig. 3 is a transverse sectional view on lines 3-3 of Fig. 1. Fig. 4 is a similar view on lines 4-4 of Fig. 1. Figs. 5 and 6 are detached perspective views of details of the invention. Fig. 7 is a perspective view of a finished clay-block as produced by the apparatus illustrated.

Referring to the drawings throughout which like reference numerals indicate like parts, 1 is the discharge end of a cutting table upon which a column of clay is cut into blocks or bricks B, the cut surfaces forming the lateral or side edges of the finished brick, and the major axis of the brick being transverse to the longitudinal axis of the cutting table and to the direction of travel of the clay column, and 2 is a platform over which the blocks B are moved before being deposited on an endless belt or apron 3. Said apron is operatively mounted upon suitably driven pulleys 5 and 6 supported in a table or frame 4 and its upper portion is caused to travel in the direction of the arrow in Fig. 1 at a higher rate of speed than the speed of travel of the advancing column of blocks, whereby the blocks are automatically separated to allow for the turning movements to be presently described.

The platform 2 is formed with one side cut away so that one end of each block is deposited upon said moving apron 3 before the opposite end is pushed beyond its support upon the portion 2¹ of the platform, whereby the first-mentioned end of the block is carried forwardly of its opposite end and thus travels for a distance upon the apron in an oblique position with relation to its line of travel. As the blocks advance on said apron their rearmost ends are intercepted by a suitable idle turning roller 7 which is rotatably mounted with a vertical axis at the side of the path of said blocks 110

and retards the motion of the rear end of said blocks sufficiently to cause the same to have their major axes directed in alinement with the longitudinal axis of the machine frame and directed to enter endwise between the side guide-rails 8, 8.

A transversely arranged idle roller 10 may be added, mounted in the frame beneath the upper portion of the apron 3 having a 10 circumferential ridge, indicated at 11, which engages the underside of said apron and upon which the middle portion of the advancing block rests when the rear end thereof is intercepted by said roller 7. The ridge 15 11 thus affords a medial pivotal point upon which the block is readily turned. The clay blocks move progressively forward upon the apron and are therefrom deposited upon a polished metal plate 12 whereupon they are 20 slidably advanced in a continuous end-to-end column by the frictional contact of the moving blocks resting upon the apron 3. The blocks upon the latter are at first spaced apart but toward the forward portion of the 25 apron between said guide-rails the resistance of the moving column of blocks upon said plate 12 causes them to close up until the accumulated frictional hold of the blocks upon the apron is sufficient to push the column forwardly upon said plate.

Corner beveling knives 13, 13 are adjustably positioned in holders 15 rigidly mounted in posts 16 at each side of said moving column of blocks and adapted to make a 35 shearing inclined cut along the upper longitudinal edges of the blocks forming the beveled corners 17, as clearly indicated in Fig. 7.

18, 18 indicate ridge-forming tools adjustably secured in vertical spaced relation 40 in posts 20 and projecting into the path of said moving column of blocks for the purpose of raising parallel ridges 21 upon a lateral side of the brick. Said ridge-forming tools may be of any suitable construction 45 but, as utilized and illustrated, each consists in a shank 22 having at its outer extremity a pair of spaced thin-edged converging pallets 23 adapted to be engaged by the plastic material of the blocks and 50 mold the same into a raised ridge, as described. As the column of blocks advances upon leaving said ridge-forming tools, it is engaged by a roller 25 mounted with a vertical axis of rotation and adapted to resiliently bear upon the side edges of the blocks 55 upon which the ridges were formed and flattening said ridges approximately to the normal plane of the block edge. Said roller is 60 formed with a plurality of vertically arranged grooves 26 spaced symmetrically about its perimeter into which the ridge ma-

terial impresses to form lugs 27 projecting from the side wall of the block. Said rollers, as illustrated, are pivoted at 30 in 65 swinging arms 28 and yieldingly pressed against the column of clay blocks by means of a tension spring 31. The blocks are then discharged from the plate 12 upon a conveying apron 32 and conveyed where desired.

Having described my invention, what I claim, is—

1. The combination with a machine for forming brick blocks of a ridge-forming 75 tool, said ridge-forming tool having two converging curved blades that are disposed to enter the face of a soft brick block to form a ridge thereon.

2. The combination with a machine for 80 forming brick blocks of a ridge-forming tool having converging curved blades adapted to enter the face of a soft brick block to form a ridge thereon and a grooved roller 85 to compress portions of the ridges formed by said ridge-forming tool and produce lugs on the face of said blocks.

3. A machine of the class described comprising a moving apron upon which brick blocks are advanced in side to side relation, 90 a transverse roller beneath said apron, said roller having a circumferential ridge that forms a pivot for advancing brick blocks and a device for engaging one end of said blocks to turn said blocks into end to end 95 relation.

4. A machine of the class described, comprising a platform over which brick blocks are moved in side to side relation, said platform having an angular discharge end and 100 an apron to receive said blocks, said apron being movable at a speed greater than the speed of movement of said blocks, whereby said blocks are turned into an angular position as they are delivered from said platform.

5. A machine of the class described comprising a platform for brick blocks, said platform having an angular discharge end, a moving apron upon which brick blocks 110 are delivered in an angular position, a transverse roller beneath said apron, said roller having a circumferential ridge that forms a pivot for advancing brick blocks, and means engageable with an end of said brick 115 blocks to turn said brick blocks in end to end relation as they pass over said transverse roller.

Signed at Seattle, Wash., this 27th day of May, 1914.

JAMES GEORGE ADDERSON.
